UNITED STATES PATENT OFFICE

2,554,796

UNIFORM FEEDER FOR GRANULAR MATERIAL

Frederick L. Runninger, Lakewood, Ohio, assignor
to Iron Fireman Manufacturing Company,
Portland, Oreg.

Application January 27, 1947, Serial No. 724,531

5 Claims. (Cl. 198—213)

1

This invention relates generally to conveyors and feeders and particularly to a feeder for granular material.

The main object of this invention is to provide a feeder by means of which coal or other material may be fed in a uniformly continuous stream past a given point.

The second object is to make it possible to maintain a non-fluctuating feeding rate for material being discharged from a worm or screw-type of conveyor.

I accomplish these and other objects in a manner set forth in the following specification as illustrated in the accompanying drawing, in which:

Fig. 1 is a side elevation of the discharge end of a worm conveyor with a portion broken away in longitudinal section.

Fig. 2 is an end elevation of Fig. 1, showing the apertures partially closed.

Fig. 3 is a view similar to Fig. 2, showing the apertures opened.

Fig. 4 is a perspective view of the unit, showing the relation of the various parts.

Fig. 5 is a collective view of the various parts in their order of assembly.

Referring in detail to the drawing, there is shown a common form of hopper 10 having at its outlet end a clean-out housing 11 provided with a removable gate 12 which is normally held in position by a screw 13 which is operated by the hand wheel 14. Flanged to the housing 11 is a coal tube 15 within which is, revolvably mounted, a coal feeding worm 16 by means of which coal 17 is drawn from the hopper 10 and delivered to the transfer housing 18 such as commonly used in connection with pneumatically fed stokers commonly referred to as the spreader type.

Referring particularly to my invention, same will be seen to consist of a sleeve 19 which is mounted on the reduced end 20 of the worm shaft 21.

On the sleeve 19 is formed a disk 22 having the apertures 23 formed therein.

Rotatably mounted on the sleeve 19 is a control disk 24 having the spokes 25 projecting therefrom, which spokes constitute closures for the openings 23. Each spoke 25 has formed, along

one edge, the inclined blade 26. One of the spokes 25 has disposed thereon, a rivet head 27, which receives the hook 28 of the helical spring 29 which encircles the sleeve 19. The end 30 of the spring 29 is outturned to enter an opening 31 in the collar 32 which can be secured to the sleeve 19 by means of the set screw 33.

It will be noted that the blades 26 project through the openings 23 into the space around the flight of the worm 16. The operation of the device is as follows: Assuming that the coal 17 is to be discharged into the transfer housing 18 and that this coal is being fed from the hopper 10 by means of the worm 16, it follows that the outlet of the tube 15 has been closed by means of the disk 22, whose apertures 23 are closed by the spokes 25 under the urging of the spring 29.

As the tube 15 fills up and pressure is exerted against the blades 26, they cause a partial rotation of the disk 24 in an opening direction, permitting coal to pass through the openings 23 and fall into the transfer housing 18.

It will be noted that by this construction, the feeding will not be intermittent but will be always continuous since the coal tube 15 will normally be full at its discharge end as long as there is coal in the feeder.

It can be seen that the loose material 17 being conveyed to the worm 16 is forced against the bent ends 26 of the shutter or disk 24. These bent sections are inclined in the direction of rotation of the worm 16 so that as the shutter disk 24 rotates, it tends to dig into the loose material being discharged from the end of the feed worm. The thrust of the material 17 against the members 26 causes them to rotate in relation to the feed worm just sufficiently to discharge the amount of material conveyed to it by the feed worm.

40 The spring 29 tends to close the shutter disk 24 against the flow of material. The amount of pressure developed between the end of the feed worm and the disk 22 can be regulated by adjusting the amount of torsion of the spring 29.

45 It can readily be seen that with this device the conveyor worm builds up a pressure behind the disk 22 and the material is discharged through the disk 22 in a non-fluctuating manner, in accordance with the amount of material delivered to it by the worm. Without this unifeed device,

the discharge rate of material from the worm would vary from a maximum to a minimum in each revolution of the worm, depending upon the relative position of the worm flight.

I am aware that numerous forms of feeders have been constructed in the past. It is, therefore, not my intention to cover such devices broadly, but I do intend to cover such forms and modifications thereof as fall fairly within the appended claims.

I claim:

1. A tubular conveyor for granular material, in combination with a conveying screw within said tube, a perforated disk forming a closure for said tube, said disk having a shutter plate 15 controlling the openings therein, responsive to pressure built up in the material delivered by said conveyor.

2. A feeder for granular material having in combination a tube, a worm conveyor within said tube, a perforated disk forming a partial closure for said tube, said disk having spring closed covers for said openings and means tending to uncover said openings and relieve the coal pressure built up by the worm of said conveyor.

3. A feeder as described in claim 2, characterized by having a spring for urging said covers toward a closed position and having wings on said covers engaging the fuel in said conveyor and tending to open said conveyor.

4. A feeder for granular material, having in combination a conveyor worm within said tube, a perforated disk forming a partial closure for said tube and secured to the worm, a shutter plate 35 revolvably mounted on said perforated disk,

wings on said shutter plate projecting through said perforated disk into the tube section of the conveyor and extending in the direction of rotation of the feed worm and a torsion spring between said perforated plate and wings adapted to urge said wing members to obstruct the openings in said perforated plate.

5. The combination of a coal conveying tube having a coal conveying screw mounted therein 10 with a perforated disk forming the end of said screw and revolvable therewith, a shutter mounted on said disk revolvable with relation to said disk, said shutter having wings thereon projecting through the disk openings inclined in the direction of the worm of said feeding device and an adjustable spring for urging said shutter toward a closing position.
